UNITED STATES PATENT OFFICE.

GUSTAV STROM, OF PONTIAC, MICHIGAN, ASSIGNOR OF FORTY-NINE ONE HUNDREDTHS TO PETER D. JOHNSTON, OF PONTIAC, MICHIGAN.

APPARATUS FOR FORMING ORNAMENTAL FACINGS.

Application filed July 3, 1922. Serial No. 572,696.

To all whom it may concern:

Be it known that I, GUSTAV STROM, a citizen of the United States of America, residing at Pontiac, in the county of Oakland and State of Michigan, have invented certain new and useful Improvements in Apparatus for Forming Ornamental Facings, of which the following is a specification, reference being had therein to the accompanying drawings.

The invention relates to the manufacture of building blocks and has more particular reference to the forming of blocks with ornamental facings. For instance, it is sometimes desired to form of cement blocks a structure having the appearance of a brick building. It is therefore an object of the present invention; first, to provide a simple method for producing the desired ornamental appearance, and; second, to provide a simple construction of apparatus for carrying out the method, as more fully herein-after set forth.

In the drawings:

Figure 1 is a perspective view showing a portion of a building block having an ornamental face;

Figure 2 is a central longitudinal section through the apparatus used for producing the ornamental facing;

Figure 3 is a cross-section thereof;

Figure 4 is a perspective view of a modified form of apparatus which may be employed for the same purpose;

Figure 5 is a cross-section through a portion of the mold for the block having the construction shown in Figure 4 applied thereto.

In the manufacture of concrete building blocks it is usual to form the same in molds in which the material is tamped or pressed and, after sufficiently set to retain its shape, the block is removed from the mold. The outer facing of the block may be formed of material having a different color or appearance from the body material, but where this facing also has a distinctive structural appearance, as, for instance, in imitation of brick, special means is required for the production of the same. With my improved method I produce this appearance by first molding the body of the block, striking off the same to form a plane surface and then superposing upon this surface material hav-

ing the desired color and structural arrangement, which, by contact with the moist body, will adhere thereto. 55

The molding of the body block may be accomplished by any suitable apparatus which is unnecessary to show or describe in detail. Preferably the mold for the block is open at the top and after the body material is filled therein, the surplus is removed by striking off, leaving a plane surface. When employing the apparatus shown in Figures 2 and 3, the facing material is deposited upon the struck-off face of the block by rolling the apparatus over such surface, which, as will be presently described, will deposit the facing in the desired structural arrangement. 65

In detail, the apparatus shown in Figures 2 and 3 comprises a cylindrical casing A having circular heads B at opposite ends thereof and a central axle C on which said heads are journaled, said axle extending beyond the heads and being provided with handles D for non-rotatively holding the same. The peripheral portion of the casing A is subdivided by rings E and cross bars F into the outlines of laid brick and between these rings and cross bars are open spaces for the deposit of the facing material. G is a hopper-shaped casing within the casing A which is non-rotatively supported by the axle C. In the lower part of this casing G is a perforated screen H above which is arranged a rotary agitator I, which, when revolved, will cause the sifting of the material through the screen. J is a discharge spout below the screen, which extends longitudinally of the casing A and is preferably restricted in width to substantially that of the cross bars F. K is a scraper on one side of the spout J which wipes the inner face of the cross bars F and rings E during the revolution of the outer casing A. L and M are intermeshing gears, the former mounted upon the casing A and the latter upon the shaft N of the rotary agitator I, so that during the rolling of the casing the agitator is also revolved. O are wedge-shaped partitions in the spout J which register with the rings E and direct the sifted material upon opposite sides thereof. 90

With the apparatus as just described, when it is desired to face the molded block, the casing A is rolled over the surface thereof,

being preferably supported by tracks or rails P formed by the sides of the mold for the body of the block. The operator then grasps the handles D, rolling the casing A over the tracks P, which at the same time revolves the agitator and sifts the facing material through the screen H, into the spout J and on to the surface of the molded block. The surplus material is struck off by the scraper K and will therefore leave a plane surface, which, however, is interrupted by the divisions formed by the rings E and cross bars F. These rings and cross bars are preferably rounded, as shown, so as to produce the appearance of the mortar lines in between the laid brick. As has been stated, the material deposited on the body of the block comes into contact with the moist surface thereof and as this facing material also contains cementitious ingredients, the moisture communicated thereto will cause proper setting.

With the modified construction shown in Figures 4 and 5, in place of using a rotary tool shown in Figures 2 and 3, a grid such as Q, is laid upon the body mold and the facing material is then deposited on this grid and struck off. When the grid is removed, it will leave the line surface having the same appearance as that shown by the method previously described.

What I claim as my invention is:

1. An apparatus for producing ornamental facings upon cement blocks, comprising a rotary pattern, and means operated by rotation of said pattern for depositing facing material in the open spaces of the pattern during the rolling of the same over the surface of the block.
2. An apparatus for forming ornamental facings on cement blocks, comprising a revoluble casing having a pattern periphery with open spaces therein, a non-revoluble receptacle within said casing, and means operated by the rolling of said casing over the surface of the block for depositing facing material in the open spaces and in contact with the surface of the block.
3. An apparatus for forming ornamental facings of dry material on cement blocks, comprising a cylindrical casing having an ornamental pattern in the periphery thereof with open spaces between portions thereof, a receptacle within said casing for the dry facing material, and means operated by the rolling of said casing over the surface of the block for depositing the material from said receptacle in the open spaces of the pattern.
4. An apparatus for forming ornamental facings of dry material on cement blocks, comprising a cylindrical casing having a patterned peripheral surface with open spaces between portions thereof, a receptacle within said casing for holding the dry fac-

ing material, a non-revoluble axle for said casing projecting outward beyond the same and provided with handles, said receptacle being held non-revoluble by said axle, and mechanism operated by the revolving of the casing when rolled over the surface of the block for agitating the material in said receptacle and depositing the same in the open spaces of the pattern.

5. An apparatus for forming ornamental facings of dry material on cement blocks, comprising a cylindrical casing having a patterned periphery with open spaces between portions thereof, a non-revoluble axle for said casing having projecting ends forming handles for holding the same from revolving, a receptacle hung upon said axle within said casing for holding dry facing material, said receptacle having a discharge spout for depositing the material in the open spaces of the pattern, and means operating during the rolling of the casing over the block for sifting the material from said receptacle into said spout.

6. In an apparatus of the class described, a movable casing having a pattern periphery with open spaces therein, a receptacle in the casing containing facing material, said receptacle having a discharge opening, a spout engaging with the discharge opening, a means adapted to discharge the facing material into the open spaces of the pattern periphery of said casing, means for moving the casing, and means in the receptacle adapted to be operated when said casing is moved for discharging facing material from the outlet opening in the receptacle into the spout.

7. In an apparatus of the class described, a movable casing having a pattern periphery with open spaces therein, means for moving the casing, a receptacle in the casing containing facing material, said receptacle having a screened opening for discharging the facing material into the open spaces in the pattern periphery of the casing, an agitator for sifting the material through the screened opening of the receptacle, and a driving connection between said agitator and casing.

8. In an apparatus of the class described, the combination with a movable casing having a pattern periphery with open spaces therein, of a receptacle in the casing containing facing material, said receptacle having a screened outlet opening, a spout in communication with the outlet opening adapted to discharge the facing material into the open spaces in the pattern periphery of the casing, a scraper for wiping the pattern periphery of said casing in advance of the spout, an agitator in the receptacle for sifting the material through the screened outlet opening of the receptacle, means for moving the casing, and a driving connection between said agitator and casing.

9. In an apparatus of the class described, a revoluble casing having a pattern periphery with open spaces therein, a shaft extending through the casing, means secured to said shaft for rolling said casing, a receptacle for facing material mounted on the shaft in the casing having an outlet opening in communication with the open spaces in the pattern periphery of the casing, and means operated by the rolling of said casing for discharging the material from the outlet opening in the receptacle into the open spaces in the pattern periphery of the casing.

In testimony whereof I affix my signature.

GUSTAV STROM.
